UNITED STATES PATENT OFFICE.

HERBERT G. DORSEY, OF EAST ORANGE, NEW JERSEY, ASSIGNOR TO WESTERN ELECTRIC COMPANY, OF NEW YORK, N. Y., A CORPORATION OF ILLINOIS.

TELEPHONIC TRANSMISSION-CIRCUIT.

1,145,978.

Specification of Letters Patent. Patented July 13, 1915.

Application filed September 7, 1912. Serial No. 719,208.

To all whom it may concern:

Be it known that I, HERBERT G. DORSEY, a citizen of the United States, residing at East Orange, in the county of Essex and State 5 of New Jersey, have invented a certain new and useful Improvement in Telephonic Transmission-Circuits, of which the following is a full, clear, concise, and exact description.

10 This invention relates to improvements in a telephonic transmission circuit and more particularly to a circuit including a telephonic relay or repeater for linking two talking circuits together for the purpose of 15 reinforcing or renewing the currents employed in telephonic transmission.

The object of this invention is to provide improved means for eliminating or reducing to a great extent the tendency of the telephonic relay to produce disturbing noises 20 on the line due to the mutual action of the receiver and transmitter elements commonly called singing, without perceptibly affecting the quality or volume given by the repeater.

25 This disturbance or singing is due to various causes, one being the character of unbalance in the two linked circuits, another and probably the predominating cause being inherent qualities of the repeater which determine the 30 prominent peak of the energy factor curve; that is the highest point of a curve obtained by plotting the frequency of the input currents in pulsations per second against the energy factor which is the ratio of the output 35 energy in the transmitter to the input energy in the receiving coil.

In accordance with this invention means are provided for decreasing the energy factor at the frequency of singing by means of 40 a connection, including apparatus for offering less impedance to the telephonic currents transmitted at or about the singing frequency of the telephonic relay, thus reducing the energy factor at this frequency 45 to a very low value. This connection contains an inductance, a capacity and resistance, either or all of which may be made variable, and may be connected either around the receiving element, the transmitter button 50 or the repeating coil, the first arrangement being the preferable one. By varying the relation of the resistance inductance and capacity the impedance of the circuit containing them is varied.

55 In the drawing illustrating this invention,

Figure 1 shows diagrammatically one embodiment of this improvement; Figs. 2 and 3 show diagrammatically different manners in which the invention may be practised, and Fig. 4 shows curves of a repeater with and 60 without the invention applied thereto.

There is shown in the present instance a metallic telephone main line extending between stations A and B and having an intermediate station C. The station C divides the line into two sections or links and has located thereat a current reinforcing message repeating or relay apparatus 5 comprising a receiving element 6 in a bridge connecting the main line conductors. A 70 transmitter 7 of said relay apparatus 5 is included in a local circuit containing the primary winding 8 of an induction coil 9 and a battery or like source of electrical energy 10. The secondary winding of the 75 coil 9 is electrically divided into four sections 11, 12, 13 and 14, these sections being connected in pairs upon opposite sides of the bridge containing the receiving element 6. Connected in shunt of the receiving element 6 in Fig. 1 is a condenser 20 and an inductive resistance 21 having an adjustable core 22, the movement of which varies the frequency of resonance of the shunt circuit. When connected in this manner the devices 80 85 shunt the incoming energy.

In Fig. 2, the apparatus is shown as connected around the transmitter element 7 in which relation the generated energy is 90 shunted.

In Fig. 3, which is another form, the condenser 20 and inductive resistance are connected around the primary winding 8 of the induction 9 and shunt the outgoing energy. 95

In Fig. 4 are shown two energy factor curves taken with a repeater, the transmitter element of which is provided with a vibrating member having a naturally high frequency. The solid line curve gives the 100 values of the energy factor at different frequencies of a repeater without the resonant shunt and the dotted line curve gives the values of the energy factor at different frequencies of the same repeater with the shunt 105 applied thereto. As will be noted from these curves the energy factor of the repeater reaches a maximum at a frequency of about 2200 and 2400 pulsations per second, whereas with the shunt applied thereto this 110

energy factor is reduced to a comparatively low value at about the same frequency. Inasmuch as the tendency of the repeater to sing is normally at the highest value of the energy factor, this tendency will be overcome if means are provided for reducing the energy factor at the singing frequency and this is done by means of the shunt as hereinbefore described. The low energy factor at the particular frequency of about 2200 pulsations per second will not appreciably affect transmission as it has been discovered that very little telephonic transmission takes place at this frequency. By varying the capacity and inductance the energy factor can be reduced to any desired frequency and to almost any desired degree, thus providing for the elimination of singing in repeaters of different characteristics.

20 I claim:

1. The combination with a telephone circuit, of a telephonic relay associated therewith, and means for rendering said relay relatively less capable of amplifying currents having a frequency equal to the natural period of said relay than of amplifying currents of other frequencies.
2. The combination with a telephone circuit, of a telephonic relay associated therewith, and an auxiliary circuit for rendering said relay relatively less capable of amplifying currents having a frequency equal to the

natural period of said relay than of amplifying currents of other frequencies.

3. The combination with a telephone circuit, of a telephonic relay associated therewith, a shunt circuit for said relay and apparatus in said shunt circuit rendering it resonant to currents having a frequency equal to the natural frequency of the said relay.

4. The combination with a telephone circuit, of a telephonic relay having a high natural frequency associated therewith, a shunt circuit for said relay and apparatus in said circuit rendering it resonant to currents of a frequency equal to the natural frequency of said relay.

5. The combination with a telephone circuit, of a telephonic relay having a natural frequency above normal maximum telephonic frequencies associated with said circuit, a shunt for said relay and apparatus in said shunt rendering it resonant to frequencies above normal maximum telephonic frequencies.

In witness whereof, I hereunto subscribe my name this 30th day of August A. D., 1912.

HERBERT G. DORSEY.
